(57) **CLAIM**

The ornamental design for a watch, as shown and described.

DESCRIPTION

FIG. 1 is a front view of a watch;

FIG. 2 is a left side perspective view thereof;

FIG. 3 is a rear view thereof; and,

FIG. 4 is an enlarged fragmentary view of the rear of the watch case.

FIG. 4 is shown as a fragmentary view for ease of illustration. The broken lines shown in FIGS. 3 and 4 are for illustration only and form no part of the claimed design.

1 Claim, 3 Drawing Sheets**FIG. 1**

FIG. 3

FIG. 4
